UNITED STATES PATENT OFFICE

139,350

DESIGN FOR A DOLL

Mary G. Schoenherr, Detroit, Mich.

Application August 12, 1944, Serial No. 114,862

Term of patent 7 years

(Cl. D34—4)

To all whom it may concern:

Be it known that I, Mary G. Schoenherr, a citizen of the United States of America, residing in Detroit, in the county of Wayne, State of Michigan, have invented a new, original, and ornamental Design for a Doll, of which the following is a specification, reference being had to the accompanying drawing, forming a part thereof, wherein:

Fig. 2 is a side view of the doll illustrated in Fig. 1;

Fig. 3 is a rear view of the doll illustrated in Fig. 1, and

Fig. 4 is a top view of the doll shown in Fig. 1.

I claim:

The ornamental design for a doll, substantially as shown.

MARY G. SCHOENHERR.
